UNITED STATES PATENT OFFICE.

GEORGE F. WELLS, OF SAN FRANCISCO, CALIFORNIA.

ELECTRICAL WAFFLE IRON.

Application filed March 3, 1922. Serial No. 540,686.

To all whom it may concern:

Be it known that I, GEORGE F. WELLS, a citizen of the United States, and a resident of the city and county of San Francisco, 5 State of California, have invented a new and useful Electrical Waffle Iron, of which the following is a specification.

The present invention relates to domestic cooking devices, more particularly of the 10 portable type, a form of which is here represented as a waffle iron, although it is to be understood that my invention may be embodied in other types of utensils.

It is an object of the present invention to 15 provide in an electrical cooking utensil having hingedly connected parts, means simplifying the electrical connections and wiring of the device for the distribution of an electrical current to the various so-called electric 20 heating elements that may be employed.

It is another object of the invention to provide especially an improved type of electrical connection and hinge joint in electrical devices where parts are hingedly connected and each of the parts is provided 25 with an electrically energized instrument; the improved hinge joint providing for the arrangement of the wiring in a concealed and protected manner wholly within the elements 30 of the hinge joint.

Another object of the invention is to provide a simple, inexpensive and practical hinge connection joining upper and lower shell sections of the utensil, so that the upper section may automatically lift or laterally move with respect to the complementary section during the cooking of a waffle to compensate for the expansion of a batter, 35 while it is cooking. In this connection it is an object to provide a hinge connection of light and substantial construction of stamped sheet metal. Further, an object is to provide for the limitation of the upward movement of the top section or shell by engagement of one portion of one hinge leaf 40 with an embossed part of the other leaf.

It is an object to provide for the covering of outlet apertures provided in the shells and through which pass electric conductors 45 threaded from one shell to another beneath the hinge leaves. An object is to provide for the concealing of the electric conductors by the hinge structure without perforating the movable leaf and to secure clearance of the conductors by embossed portions of the leaves. 55

Another object is to provide for the safe fastening of the sections together in such manner as to prevent the accidental disconnection of the sections, as may be caused by 60 repeated relative movement of the sections about the axis of the hinge.

The invention possesses other objects and features of advantage, some of which, with the foregoing, will be made manifest in the 65 following description of the preferred form of the invention, which is illustrated in the drawings accompanying and forming part of the specification. It is to be understood that it is not intended to limit the invention 70 to the embodiment shown by the said drawings and description, as variations may be adopted within the scope of the invention as set forth in the claims.

Fig. 1 is a side elevation of an embodiment of the invention in a waffle iron. 75

Fig. 2 is a rear elevation of the same.

Fig. 3 is a sectional view of the upper shell section with the associated parts.

Fig. 4 is a perspective of the detached 80 sheet metal hinge showing the parts in scattered, but approximate relation.

Fig. 5 is a sectional view of a portion of the lower or bottom shell section and its hinge connection. 85

Fig. 6 is a longitudinal central section through the hinge structure taken on the planes indicated at line 6—6, Fig. 5.

The invention in the present instance is shown as embodied in a cooking utensil having 90 a pair of hingedly connected shell sections which may be made in any desired manner and of any desired material, each of the shell sections being substantially bowl-shaped and provided with cooking means, comprising waffle plates, which are arranged in the respective shell sections and are adapted to be brought into overlapping face to face position in the usual manner of waffle irons. 95

One feature of the invention resides in means for so connecting the sections together that during the cooking of a waffle, the upper section may be bodily lifted in parallel relation to the lower section due to 100 the expansion of the batter being cooked.

The sections are preferably of duplicate construction as to their major details, so that they may be utilized in the device as either the top or the bottom of the shelf; each section being provided at one side with an aperture or "outlet", set back from the 110

rim of the shell and through which electric conductors may be threaded from section to section through a hinge structure connecting the sections.

5 More particularly in the illustrated embodiment of the invention, the utensil consists of a shell-like bottom section 2, on which there may be secured or provided, in any desired manner, suitable legs 3, and these may 10 be secured to a base 4. Complementary to the bottom shell 2 is a top or upper shell 5, and these are adapted to be assembled in a closed position or one may be lifted from the other, as, for instance, by being turned about a 15 hinge joint connecting them.

A simple joint is shown as including hinge parts which, preferably, to secure economy of cost, are made of sheet metal stampings. The upper hinge leaf is of shell-like form 20 having a body 6 approximating a section of a cylinder and has, at its ends, laterally extending wings, which may be termed "lands", 6', stamped to conform to the curvature at one side of the flange or rim of 25 the upper section 5 to which the leaf may be secured, as by rivets or other fastenings 7 passing through the "lands" 6'. At the ends of the body 6 of the leaf are provided cheeks or lugs 6^a at right angles to the length of 30 the body and these have downwardly extending eye forming parts 8 perforated at 9. These parts may be termed therefore, eyes and are spaced in parallel and co-axial position, so that a fastening bolt 10, may be 35 disposed in the eyes, as will be explained hereinafter. The lower leaf consists of a substantially cylindrical body 11 having a diameter slightly larger than the diameter of the aperture 9 of the eyes and has a length 40 slightly less than the distance axially between the eyes 8 of the hinge leaf 6, so that the cylindrical body 11 of the lower hinge leaf can be arranged substantially co-axially with the eyes. Extending down from the 45 body 11 is a wing or land forming portion 11^a perforated, as at 12, to receive means for fastening it to the adjacent side of the lower section 2 of the utensil.

The sections 2 and 5 to which the respective hinge leaves 6-11 have been secured may be assembled so as to bring the cylindrical leaf body 11 between the eyes 8 of the complementary leaf 6 and then means are applied to pivotally connect the hinge 50 leaves, and further, the connecting means are adapted to be held against removal and dislocation by means of the bolt or equivalent bolt 10 or an equivalent fastener. The pivot forming means preferably consists of a pair of pieces, which may be 55 appropriately referred to as buttons. Each button has a cup-shaped or countersunk body 13 having an exterior diameter to permit it to be disposed in a respective aperture 9 of an eye 8 of the hinge leaf 6; the

bottom of the button being perforated, as at 14 to receive the shank of the fastening bolt 10. Each button has at one end an outwardly extending flange 15 to bear against the outer face of the adjacent eye 8 in which it may be mounted. The flange 15 and the ring-like portion of the eye 8 may be of approximately the same exterior diameter and preferably the axis of an opening 9 of an eye is shown disposed with relation to the outer face of the contiguous end wing or leaf 6', so that by flattening one side of a flange 15, as at 15^a, the button will be prevented from rotation when, after the bolt 10 has been inserted 80 so that its head will bear in the cavity of one button and its threaded end will be exposed in the cavity of the other button, the nut 10^a is being screwed into place on the exposed end of the bolt. This, therefore, insures the rotation of the bolt 10 and its nut 10^a with the buttons 13, as the upper section 5 is raised and lowered.

In order to provide for the desired free vertical bodily movement of the upper section during expansion of the batter, the cylindrical body 11 of the lower hinge leaf has an internal diameter materially more than the exterior diameter of the bearing-forming body portion 13 of the button 85 which projects inwardly through its respective eye 8 of the upper hinge leaf 6. The lower section 2 of the utensil being regarded as stationary, as is also its hinge part 11, during the cooking the top section 5 is therefore free to move upwardly because of lost motion between the body of the buttons 13 mounted in the upper hinge leaf, and the chamber of the cylindrical body 11 of the lower hinge.

Within each of the shell sections there is provided a waffle plate P having the usual waffle face design and between the shell section and the waffle iron is arranged any suitable heating element E, electrically energized, as by an electric current traversing circuit conductors C passing through the aperture 5' of the upper shell and thence through the hinge leaves and into the lower shell 2 through an aperture 2 so that the conductors may be appropriately connected to suitable terminals T.

A feature of the invention resides in the construction of the hinge members 6 and 11 providing clearance for the conductors C and also providing for the covering and protection of the conductors and permitting unrestricted opening and closing of the top shell. Such clearance and protection is afforded by providing the upper hinge leaf 6 with a suitably located outwardly embossed portion 6^b struck up, as shown in Fig. 5, between the ends of the cylindrical portion of the leaf. The lower leaf is embossed, as at 11^b between the ends of the

land portion 11^a; the embossed portions 6^b and 11^b registering with the conductor outlets 2' and 5' of the shell sections and therefore completely covering the outlets and the conductors. The sleeve part 11 of the lower hinge may be apertured, as at 11^c to permit the threading of the conductors across the cylindrical part and around the shank of the bolt 10, thus providing for the easy threading or wiring of the attached sections 2 and 5, after they have been pivotally connected by the arrangement of the buttons 13 in the eyes 8 and in the end of the sleeve 11.

15 The embossment 11^b of the lower hinge also has the function of serving as a stop to limit the opening movement of the upper section 5, this being accomplished as the exposed longitudinal edge 6^b swings into engagement with the contiguous part of the embossment 11^b.

From the above it will be seen that I have provided a shell-like hinge construction of extremely inexpensive type and of the necessary rapidity and strength, the whole blending well into the general design of the utensil to make a safe, as well as attractive article. The cylindrical boss of the hinge leaves roll substantially one 25 within the other during the opening and there are no unsightly spaced lugs or sockets or gaps in the construction of the hinge apparent to view.

The length of the bearing area of the hinge also causes the substantial accurate registration of the upper shell on the lower shell, when the iron is closed, thus obviating the necessity of dowels in the rim, which have heretofore been employed. The hinge 30 also serves to cover and protect the electric conductors when the iron is open, as well as when it is closed.

I claim:

1. An electrical cooking utensil having upper and lower cooking element-carrying sections and a hinge structure connecting said sections and including a leaf member having a pair of spaced co-axial journal eyes and having lands to be secured to one 45 of said sections, a sleeve fitting between said eyes and having a land part attachable to a section of the utensil, and means for connecting the sleeve and the leaf member.

2. An electrical cooking utensil having upper and lower cooking element-carrying sections and a hinge structure connecting said sections and including a leaf member having a pair of spaced co-axial journal eyes and having lands to be secured to one 55 of said sections, a sleeve fitting between said eyes and having a land part attachable to a section of the utensil, and means for connecting the sleeve and the leaf member; said means including pivot forming 60

3. In a waffle iron, a pair of sections, and a hinge connection between the sections, said connection being such that there is a substantial amount of play between the parts of the hinge to permit the adjacent faces of the sections to be separated in a direction substantially perpendicular to the faces, whereby the variations in the thickness of the batter during cooking are compensated. 70

4. In a waffle iron, a pair of sections, a hinge pivot carried by one of said sections and a hollow tube carried by the other and encompassing the pivot, the internal diameter of the tube being substantially larger than the external diameter of the cooperating pivot, whereby the variations in the thickness of the batter during cooking are compensated. 75

5. In a waffle iron, a pair of sections, and means for pivotally connecting the sections so that they may be placed with their faces adjacent each other, comprising a hinge leaf carried by one of the sections, a pivot fastened to the leaf, a cooperating hinge leaf carried by the other section and having a 80 tubular member with an internal diameter substantially larger than the external diameter of the cooperating pivot, whereby the variations in thickness of the batter during cooking are compensated. 90

6. An electric waffle utensil having upper and lower shell sections each carrying a waffle iron, the shells having wire outlets at one side, and sheet metal leaves attached to said sections and being pivotally connected, each leaf having an embossed portion overlapping said outlets for the arrangement of electric conductors, which are concealed by the hinge structure, both when in open or closed position. 105

7. An electric waffle utensil having upper and lower shell sections each carrying a waffle iron, the shells having wire outlets at one side, and sheet metal leaves attached to said sections and being pivotally connected, each leaf having an embossed portion overlapping said outlets for the arrangement of electric conductors, which are concealed by the hinge structure; one of said leaves having spaced co-axial eyes, and the other having a sleeve fitting and pivoted endwise therebetween. 110

8. An electric waffle utensil having upper and lower shell sections each carrying a waffle iron, the shells having wire outlets at one side, and sheet metal leaves attached to said sections and being pivotally connected, each leaf having an embossed portion overlapping said outlets for the arrangement of electric conductors, which are concealed by the hinge structure; the sleeve having an aperture to receive the conductors threaded from section to section. 120

9. An electric waffle utensil having shell sections, and hinge leaves attached to said 130

- sections at one side and being pivotally connected, one leaf having spaced, co-axial eyes and the other having a sleeve extending from eye to eye and having an embossed part forming a clearance for electric conductors, the first named leaf having a part engageable with the embossed part, thereby limiting opening movement of the sections.
10. An electric waffle utensil having shell sections, and sheet metal hinge leaves attached to said sections at one side and being pivotally connected one leaf having spaced, co-axial eyes and the other having a sleeve extending from eye to eye and having an embossed part forming a clearance for electric conductors, the first named leaf having a part engageable with the embossed part, thereby limiting opening movement of the sections.
15. 11. An electric waffle utensil having shell sections, hinge leaves attached to the sections, pivot forming buttons connecting the leaves, and a bolt passing through the meeting parts of the leaves and through said buttons.
20. 12. An electric waffle utensil having shell sections, hinge leaves attached to the sections, pivot forming buttons connecting the leaves, and a bolt passing through the meeting parts of the leaves and through said buttons; said buttons having means for preventing their rotation independently of their mounting so as to prevent loosening of the bolt by movement of the sections.
25. 13. An electric waffle utensil having shell sections, hinge leaves attached to the sections, pivot forming buttons connecting the leaves, a bolt passing through the meeting parts of the leaves and through said buttons, and means for preventing the bolt from working loose by movement of the sections.
30. 14. An electric waffle utensil having shell sections, hinge leaves attached to the sections, pivot forming buttons connecting the leaves, and a bolt passing through the meeting parts of the leaves and through said buttons; said buttons having countersunk bodies in which the bolt head and the bolt nut are received.
35. 15. An electric waffle utensil having shell sections, hinge leaves attached to the sections, one leaf having eye-forming end lugs; the other leaf having a sleeve extending from lug to lug, and pivot forming buttons mount-
ed in said lugs and having bodies extending into said sleeve to form bearings therefor.
40. 16. An electric waffle utensil having shell sections, hinge leaves attached to the sections, one leaf having eye-forming end lugs; the other leaf having a sleeve extending from lug to lug, and pivot forming buttons mount-
ed in said lugs and having bodies extending into said sleeve to form bearings therefor; the sleeve loosely fitting said bodies so that bodily lateral motion is provided as between the sections.
45. 17. An electric waffle utensil having shell sections, hinge leaves attached to the sections, one leaf having eye-forming end lugs; the other leaf having a sleeve extending from lug to lug, pivot forming buttons mount-
ed in said lugs and having bodies extending into said sleeve to form bearings therefor. and means for securing the buttons in place.
50. 18. In an electric cooking utensil, a pair of sections, and means for pivotally connecting the two sections, comprising a pair of spaced lugs carried by one of the sections, means hingedly connected to the spaced lugs, and means for substantially entirely covering up that space which is formed between the hinge lugs and between the sections, whereby electrical connections between the sections led through this space may be concealed.
55. 19. In an electric cooking utensil, a pair of sections, a pair of spaced lugs carried by one of the sections, pivotal connections for the lugs to the other sections, a cover member extending between the lugs and carried by that section to which the lugs are connected, and another cover member carried by the other section, said cover members overlapping each other in such a way that electrical connections between the sections and led through the space between the lugs may be concealed.
60. 20. In an electrical cooking utensil, a pair of hingedly connected sections, cover members carried by the sections near the place where they are hinged, and an electrical connection between the sections located near this place, said cover members overlapping so that they serve to conceal the electrical connection.
65. In testimony whereof, I have hereunto set my hand.
- GEORGE F. WELLS.
